UNITED STATES PATENT OFFICE

139,016

DESIGN FOR A TOY ROCKER

William J. Kramer, Wauwatosa, Wis.

Application July 10, 1944, Serial No. 114,352

Term of patent 7 years

(Cl. D34—15)

To all whom it may concern:

Be it known that I, William J. Kramer, a citizen of the United States of America and a resident of Wauwatosa, in the county of Milwaukee and State of Wisconsin, have invented a new, original, and ornamental Design for a Toy Rocker, of which the following is a specification, reference being had to the accompanying drawing, forming a part thereof.

In the drawing:

Fig. 1 is a three-quarter front view of a toy rocker showing my new perspective design, and
Fig. 2 is a three-quarter rear perspective view thereof.

I claim:

The ornamental design for a toy rocker, as shown.

WILLIAM J. KRAMER.
